TELEPHONE MESSAGE RECORDING AND
REPRODUCING APPARATUSErnest M. Wilson, Portland, Oreg., assignor to
H. A. Hartshorn, Wm. F. Klinker, and Ernest
M. Wilson, all of Portland, Oreg., as trustees

Application February 24, 1930. Serial No. 430,871

2 Claims. (Cl. 179—6)

My invention relates to telephone systems, and has for its object the automatic recording of a message communicated over the telephone, and the reproducing of the message at will.

5 A further object of my invention is to provide a relatively simple, efficient apparatus for the recording and the subsequent reproducing of a telephone message, as mentioned. In brief, to provide an apparatus which is adapted to be connected in the telephone circuit of the subscribers of the telephone system without requiring any changes in the conductors or instruments of the system; and also adapted to be actuated by the normal call signal from the central station.

15 A further object of my invention is to provide an apparatus whereby to record, for subsequent audible reproduction, both incoming and outgoing conversations between the subscribers to the telephone system, without affecting the normal operation of the telephone system.

25 A further object of my invention is to provide an apparatus whereby to deliver a conventional audible message into the substation telephone transmitter, informing the calling party that my apparatus is connected to the subscriber's telephone, and the party calling may thus proceed to speak his message in the usual manner, with assurance that the message will later be reproduced at the will of the party called.

30 Numerous telephone recording and reproducing devices have heretofore been made, but they have failed, according to my information, principally because they attempted to amplify the telephone current itself for further recording and reproduction of the telephone message. Such attempts were unsuccessful because the electric current of the ordinary telephone system is weak, and is so distorted during transmission by passing through other fields of electrical influence or by the length

40 and various kinds of conductors used, which set up minor or secondary oscillations in the current, and while such distortions do not affect the current sufficiently to change the frequencies at which the diaphragm of the telephone transmitter must vibrate to reproduce the original voice sounds; any amplification of the current tends to at the same time magnify these distortions so that the diaphragm of the sound reproducing instrument connected with the amplified current

45 will also register the minor and/or secondary oscillations set up in the current, and hence, will not reproduce the original voice sounds faithfully.

50 Therefore, a further object of my invention is to provide a telephone message recording and reproducing apparatus adapted without the use of

expensive microphones and special conductors and other auxiliary apparatus to relay and transmit the oscillations of the weak telephone current induced by the voice, to an amplified current in such a manner as to exclude the distorted or secondary oscillations of the telephone current acquired during its transmission through the telephone system and relay only the oscillations induced by the voice to thus assure a clear and perfect recording and subsequent audible reproduction capable of being magnified to any tone volume desirable.

I attain my objects in a sound reproducing system, a telephone circuit, an amplifying element, the strength of the current of the amplifying element being greater than the strength of the current of the telephone circuit, a transmitter comprising primary and secondary electro-magnets with a diaphragm therebetween, said electro-magnets connected respectively with the telephone circuit and the circuit of said amplifying element, the number of ampere turns of the primary and secondary electro-magnets being respectively proportional to the ratio of the strength of the currents flowing through them to induce magnetic fields of substantially equal force, electrically operated switches actuated by the signal current of the telephone circuit for connecting said primary electro-magnet with the telephone circuit and for closing the input circuit of said amplifying element, sound reproducing and recording elements connected with said amplifying element, mechanical means actuated by said sound recording elements for disconnecting said primary electro-magnet from the telephone circuit and the input circuit of said amplifying means when said sound reproducing means have reached their limit of operation.

These and other incidental features of my invention, the details of construction and mode of operation, are hereinafter fully described with reference to the accompanying drawing, in which:

Fig. 1 shows a diagrammatic side elevation of my apparatus and illustrates by conventional symbols the circuits and telephone instruments of my apparatus, and illustrates the mechanical construction and operation thereof; and

Fig. 2 shows a perspective detail of the mechanical means controlling the operation of the sound reproducing arm.

Referring now to Fig. 1, the usual connections with the central station are shown at GN, L1, L2. A manually operated switch *a* is provided for en-

tirely cutting off the apparatus and the telephones from the central station.

The connections of the lines GN, L1, L2, with the telephone instruments are as usual, except for supplementary automatic relays and switches placed therein which comprise the line GN connected with an electro-magnet *b* which operates a relay *c*, the equivalent of the call bell in the ordinary telephone box. The line L2 passes through the usual condenser *d* and induction coil *e* to the other side of the electro-magnet *b* and to a double, two-way, electrically operated switch *f*, *f'*. The line L2 here divides into lines *aL2* and *bL2*, the line *aL2* passing through the switch *f'* to a telephone receiving instrument *h*.

The line L1 passes through the induction coil *e* to the double switch *f*, *f'* where it divides into lines *aL1*, *bL1*, the line *aL1* passing through the switch *f'* to the receiver *h* and a transmitter *i*. The transmitter *i* is connected directly by a line *cL2* with the line L2 by which the telephone circuits are completed.

The foregoing describes the usual telephone connection, with what might be called the service telephone adapted, when the switch *f'* is closed, to be used independently of my apparatus for making an ordinary unrecorded call.

For the telephone connections with my apparatus, the lines are as follows: The line *bL2* which passes through the switch *f* is also connected with the receiver *h* and the line *bL1* is connected with both the receiver *h* and transmitter *i*. The line *dL2* through the switch *f* is directly connected with L2 and the transmitter *i*, thus these circuits are complete and since the switch *f*, *f'* is a double two-way switch, the lines *aL1*, *aL2*, and *cL2* will be closed when the lines *bL1*, *bL2* and *dL2* are open and the reverse, hence, each set of circuits may function independently of the other.

The double switch *f*, *f'* are operated by a double solenoid *s*, comprising electro-magnetic elements 2, 3, having a common floating core 4. The element 3 is connected by a line 5 with a source of power 6 and with the said relay *c* by a line 5*a* which is operated by the electro-magnets *b* in the line GN of the telephone circuits. The other side of the relay *c* is connected by a line 7 with the source of power 6.

By this arrangement, the call signal from the central station closes the relay *c* and actuates the electro-magnetic element 3 of the solenoid *s* to draw the core 4 towards it and thus close the switch *f* and open the switch *f'*; then the telephone lines *bL2*, etc., are connected with the central station.

The switch *f* also controls a line 10 connected to the line 5 and the source of power 6 and an electric motor 11, which operates the mechanical elements of my apparatus hereinafter described. The other side of the motor 11 is directly connected with the power 6 through a line 12 to complete the circuit.

The transmitting and amplifying element of my apparatus will now be described.

The telephone lines *bL1* and *bL2*, which comprise the receiver circuit, are connected through lines 20, 20*a* with an electro-magnet 22, having the same resistance as the electro-magnets of the usual telephone receiver, so as not to affect the functioning of the telephone instrument in any way. A diaphragm 23 is arranged in the field of the said electro-magnet and an electro-magnet 24 is arranged on the opposite side of the diaphragm 23. A normal air gap is provided be-

tween the said magnets on each side the diaphragm.

The magnet 24 is connected through the lines 25, 25*a* with a suitable amplifier 26, which is connected with the source of power 6 through the lines 27, 27*a*. A manual switch 28 is placed therein, but the circuit is normally closed at all times.

However, since the current of the amplifying element is stronger than that of the telephone circuit, and since the magnetic fields of each of the said electro-magnets must be equal in order to act equally on the diaphragm 24, I provide electro-magnets the respective numbers of ampere turns of which are equal to the ratio of the telephone current to that of the amplifying current, thereby providing magnetic fields of equal force.

As before mentioned, even though the telephone current has become distorted by acquiring secondary oscillations from outside influences, such distortions are not registered by the diaphragm of the ordinary telephone instrument, at its normal low voltage, but if the current is amplified, the distortions become so magnified that they are registered by the telephone diaphragm and produce an imperfect reproduction of the original voice sound induced in the telephone current. Further, such imperfect reproduction becomes more pronounced on the more sensitive diaphragms of the so-called loud speakers, especially when the volume of sound has also been magnified.

However, by the arrangement of the diaphragm 23 and the electro-magnets 22, 24, as the magnetic field of the electro-magnet 22 is varied by the oscillations of the telephone current, the diaphragm 23 will vibrate to correspondingly vary the magnetic field of the electro-magnet 24, and thus only the oscillations of the telephone current induced by the voice and which are the only oscillations registered by the diaphragm 23, will be transmitted to the amplifier circuit 25, 25*a* and the secondary oscillations or distortions, acquired during transmission from outside influences, will be excluded from the amplifier current 20, 20*a*, and hence the amplifier current may be amplified to produce a clear and faithful reproduction of the original voice sounds in any volume desirable.

125 The recording and reproducing elements of my apparatus are part electrical and part mechanical and comprise a revolute turntable 30 driven by the motor 11, through a shaft 11*a*, on which a phonograph recording disc 32 is placed, and an 130 annular supplementary, permanent reproducing disc 32*a*, circumscribing the disc 32 and having recorded thereon a conventional message, to the effect that, "This is the telephone of J. Smith and is connected to an automatic recording and 135 reproducing apparatus, please speak your message clearly."

140 Of course, while I have shown the well known phonograph disc, any other suitable recording device may be used, such as a cylindrical record as used in a dictograph, or a continuous strip or wire which is adapted for having sound grooves inscribed thereon.

145 Adjacent one side the turntable is provided a sound recording arm 35 of suitable construction, having in its base a sound reproducing instrument 36, connected with the amplifier 26, through lines 36*a*, 36*b*, comprising the output circuit of the said amplifier, by which the message re-

produced from the amplifier will be inscribed on the disc 32.

A sound reproducing arm 40 is arranged, for convenience, adjacent the other side of the turntable and adapted to ride in the grooves of each disc 32, 32a and reproduce at the proper time the messages inscribed thereon, as hereinafter further described.

The motor 11 is also operatively connected by 10 a belt 50, with a pulley 51a carried on a shaft 51, on which are also mounted two similar pulleys 51b, 51c. The pulley 51b is connected by a belt 52 with a cam 53.

A vertically movable arm 54 is provided having a pin 54a adapted to bear on the said cam 53. A pendent arm 35a carried by the sound recording arm 35 bears on a platform on said arm 54, so that, as the arm 54 is lifted by the cam as it rotates, the sound recording arm 35 20 will be raised and lowered from the disc 32.

The pendent arm 35a is also pivotally connected with a switch arm 70 of a two-way switch 70a in the line 36b from the amplifier to the sound reproducing instrument 36 and a line 71 connected with another sound reproducing instrument 72. A line 72a connects the instrument 72 with the line 36a of the output circuit of the amplifier and thus completes its circuit. By this arrangement, when the instrument 36 is 30 connected with the amplifier, the circuit of the sound reproducing instrument 72 will be opened and the circuit of the sound reproducing instrument 36 will be closed and vice versa.

A tumbler 55 is pivoted to the free end of the 35 arm 54, and normally supports, in closed position, a switch lever 56 in a circuit formed by a line 58 connected with the line 27a and the power 6, and a line 59 connected with the element 2 of the double solenoid s. The element 40 2 is also connected through a line 59a with the line 12 and the other side of the source of power 6.

The lower end of the tumbler 55 is provided with a soft iron plate 55a, and an electro-magnet 45 61 is arranged so as to be adjacent the plate 55a, when the arm 54 is in its raised position.

The electro-magnet 61 is connected to the line 59 and a line 63a leading to a switch arm 64 operatively connected with the adjacent end 50 of the core 4 of the double solenoid s. A contact point 65 is arranged adjacent the said arm 64 and in contact therewith when the switch f is open. The contact point 65 is connected through the line 12 to the power 6. The above 55 are the automatic circuit opening and closing elements of my apparatus and will be again referred to.

The said sound reproducing arm 40 is mounted at its end on a rotatable and longitudinally movable shaft 80, which rests at its lower end on a longitudinally, horizontally, movable arm 81. The arm 81, see Fig. 2, is provided with a beveled surface 81a at one end and is so arranged that its other end bears against a cam 83, driven by a belt 84 passed over the said pulley 51c. An expansion spring 81c holds the arm 81 in contact with the said cam 83, and a hook 80b carried by the shaft 80 is engageable in an elongate slot 81b in the arm 81, so that the rotation of the cam 83 will, at the proper time, move the arm 81 longitudinally and cause the end of the shaft 80 to ride up or down on the beveled surface 81a; and at the same time the hook 80b in the slot 81b will cause the shaft to rotate, 70 and thus swing the arm 40 in a horizontal plane 75

and raise it from or lower it onto the said disc 32a for the delivery at the proper time of the said conventional message.

A circuit 40a of the sound reproducing arm 40 is connected through a make and break switch 41, with the lines 25, 25a of the input amplifier circuit which is adapted to be closed only when the arm 40 is bearing on either of the discs 32 or 32a.

In the operation of my apparatus, the switch f' being normally closed, the telephone may be used as usual by merely lifting the receiver h from the hook, not shown, by which central is called, and using the transmitter i and receiver h, to carry on the usual conversation independently of my apparatus. Also to connect the telephone circuits with central, so that they will function as an ordinary telephone, independently of my apparatus, for incoming calls, I have provided a double manual switch r in the line GN to divert the signal current from the passing through the electro-magnets b and carry it around the said relay c through a line aGN having an ordinary call bell t, connected therein.

For the receiving and recording of an incoming message, the call signal from the central station through the line GN will actuate the electro-magnets b to close the relay c and the circuit 5 through the element 3 of the solenoid s, which will close the switch f and open the switch f', thus closing the circuits 10, 12 through the motor 11 and the lines bL1, bL2, and dL2 of the telephones.

The motor 11 will then be actuated to rotate the turntable 30 and the cams 53 and 83 also 110 driven by the motor 11, but at a reduced speed.

At this time both the sound recording arm 35, and sound reproducing arm 40 are raised from the discs 32, 32a, being held so by the previously adjusted positions of the cams 53, 83. As the 115 cam 83 rotates, the end of the arm 81 will ride into the low surface 83a and cause the arm 40 to be lowered onto the disc 32a closing the switch 41 in the circuit 40a to the amplifier 26, whereby the conventional message inscribed 120 thereon, will be reproduced through the amplifier and sound reproducing instrument 72 into the transmitter i.

By the time the conventional message is finished, the cam 83 will have rotated until the 125 arm 81 rides out of the low place 83a, and the arm 40 is lifted. At this time, the cam 53 being previously so positioned will have rotated until the pin 54a of the arm 54 rides off the high place 53a on the cam 53, and the sound recording arm will then be lowered onto the disc 32 to record the message which will be spoken in reply to the said conventional message through the circuit 20, 20a, 25, 25a and the amplifier 26. At this time, of course, the switch 70a is positioned to close the circuit 36a, 36b of the instrument 36.

The apparatus will then continue to record until the cam 53 has rotated to bring the pin 54a of the arm 54 again onto the high place 53a 140 of the cam 53, and raise the sound recording arm 35. Thus the recording is stopped and the raising movement of the arm 54 causes the tumbler 55 to close the switch 56 and the circuit 58, 59 which will actuate the element 2 of the solenoid s to draw the core 4 inward and open the switch f and close the switch f' to disconnect the apparatus from the telephone system and stop the motor 11, simultaneously.

Further, as the arm 54 is raised, the soft iron 145

plate 55a on the tumbler 55 is positioned adjacent the electro-magnet 61, the circuit of which has been closed by the movement of the solenoid s and operation of the switch arm 54, so that the tumbler 55 will be caused to trip the arm 56 and open the said circuit 58, 59, to de-energize the element 2 of the solenoid s again and at the same time break the circuit of the electro-magnet 61, which, as before mentioned, is

10 also connected in the circuit 59.

Then, when it is desirable to reproduce the message so recorded, a clutch 92 on the motor shaft is disengaged so that only the turntable 30 will be driven and a switch q in the circuit 15 10 and 12 of the motor 11 is closed to actuate the latter.

The sound reproducing arm 40 is then manually lowered on the disc 32 by means of a rotatable cam disc 39, which, when rotated, permits the arm 20 50 to move downwardly on the shaft 80, and disengage itself from a locking lug 39a on the upper end of the shaft 80 so as to swing freely thereon. Thus the arm 40 will be lowered onto the disc 32, and the switch 70a in the circuit 71, 72a of the 25 sound reproducing instrument 72, being closed, since the arm 35 is raised the message will be reproduced through the amplifier 26 and the sound reproducing instrument 72.

When the message has been reproduced the 30 sound arm 40 is lifted by the cam disc 39 and re-engaged with the locking lug 39a, the switch q opened, and the clutch 92 put in engaged position again. The old disc 32 may then be removed and replaced by a new one, the old being retained 35 and filed as a matter of record, which could again be reproduced on my apparatus or any suitable phonograph.

Further, should a conversation be in progress over the telephone, independently of my apparatus, and it is desirable to have both sides recorded, the said clutch 92 will be disengaged and another cam disc 93 carried by the arm 54, which bears on the pin 54a, will be rotated so as to permit the pin 54a to lower the sound recording arm 35 onto the disc 32. Then a manual switch p in the circuit 5a, 7, is momentarily closed to cause the element 3 of the solenoid s to be actuated to close the switch f and connect my apparatus with the telephone system and actuate the motor 11 so that the message will be recorded through the 45 50 circuits 20, 20a, the electro-magnets 22, 24, and the circuits 25, 25a to the amplifier 26, which is connected to the sound reproducing instrument 36 at the base of the sound recording arm 35.

55 At this time a hose-like element 90, provided with an ear piece leading from the sound box of the sound reproducing instrument 36 is preferably used as a receiver, since the person listening will then hear positively the message being recorded.

60 The outgoing conversation through the transmitter is also recorded, because both the circuits of the receiver h and transmitter i, are, as usual,

connected to and originate from the lines L1 and L2 and hence the oscillations induced in one circuit will be reproduced in the other, and the electro-magnets 22 and 24 and the diaphragm 23 will be actuated to relay the oscillations induced by the voice in the transmitter i to the amplifier 26, and the sound recording arm 35 as well as those received in the receiver.

When the conversation is finished the cam disc 93 will be rotated to lift the sound recording arm 40 which will close the switch 56 and automatically actuate the element 2 of the solenoid s to open the switch f and close the switch f', as before mentioned. Also, the clutch 92 will again be engaged and the apparatus will again be ready for automatically receiving and recording a call from central, since the relative positions of the cams will not have been altered, and the corresponding operations of the arms 35 and 40 not changed.

Of course, in actual practice, it would be desirable to provide suitable mechanical means, whereby the disengaging of the clutch 92, the rotation of the cam disc 93, and the momentary closing of the switch p may be done simultaneously in one operation.

I claim:

1. In a sound reproducing device the combination of a transmitter and an electric telephone circuit in which the transmitter is connected, a receiver and a second electric circuit in which the receiver is connected, an amplifying element in the second circuit, and a relay element adapted to transmit substantially only the oscillations induced by the voice in the said first circuit, said relay element comprising electro-magnets connected in said circuits respectively and a diaphragm between said magnets, the strengths of said magnets being relatively proportioned to induce magnetic fields of substantially equal force on both sides of the diaphragm, means actuated by the signal current of the telephone circuit for connecting the latter with its electro-magnet, sound reproducing means and recording elements connected with said amplifying element, mechanical means actuated by said sound recording elements for disconnecting the electro-magnets from the telephone circuit and said amplifying element.

2. In a sound reproducing device the combination of a telephone circuit, and an amplifying circuit, a relay element connecting said amplifying circuit and said telephone circuit, said relay comprising electro-magnets connected in said circuits respectively and a diaphragm between said magnets, means actuated by the signal current of the telephone circuit for connecting the latter with its electro-magnet, sound reproducing and recording elements connected with said amplifying circuit, mechanical means actuated by said sound recording elements for disconnecting the electro-magnets in the telephone circuit and the amplifying circuit.

ERNEST M. WILSON.
